GARMENT

Charles H. Schopbach, Aurora, Ill., assignor to
International Corset Company, Aurora, Ill., a
corporation of Illinois

Application October 1, 1936, Serial No. 103,491

6 Claims. (Cl. 2—30)

This invention relates to foundation garments comprising corsets and brassières.

The main object of the invention is to provide a garment which will give maximum comfort to the wearer and in which the brassière is self-adjusting.

In combination garments of the character described, there is a predetermined relation between the measurements of the waistline of the corset and brassière and the bust of the brassière, and, therefore, such garments are not adaptable to all figures, and while means are usually provided for adjusting the width of the corset, no adequate provision has heretofore been made for automatic adjustment of the brassière to the figure of the wearer and to compensate for adjustments which may be made in the corset.

In the garment herein shown and described the brassière is automatically adjustable to provide variations in the predetermined waist and bust measurements for which the garment was designed.

Another object of the invention is to provide means in the brassière for controlling the dia-phragm and properly supporting the breasts of the wearer.

Another object is to provide improved means for attaching the brassière to the corset.

In the drawing:

30. Fig. 1 is a front elevation of a foundation garment embodying my invention, the lower part of the corset being broken away.

Fig. 2 is a fragmentary view of the waistline portion of the garment shown in Fig. 1, with the brassière turned upwardly at the front to disclose the means for attaching it to the corset.

The embodiment of the invention shown in the drawing comprises a front lace corset provided with a lacing-concealing panel, constructed as described in United States Letters Patent No. 2,013,190 of September 3, 1935, but the present invention may be embodied in a garment having a front or back lace corset or a non-laced corset having elastic panels, or any other suitable construction.

The corset shown consists of side panels 10, 10, front panels 11, 11, and side back panels 12, 12. The side back panels 12 and the center back (not shown) may extend to or above the waistline of the corset. If they extend above the waistline, as shown, they may constitute part of the brassière, but of course the brassière may be made of separate pieces, preferably secured to the corset at the back.

55 The panels 11, 11 are non-elastic and are con-

nected together by lacings 13. A panel 14 of laterally stretchable elastic is stitched longitudinally to one panel 11 to overlie the lacings 13, and at its free longitudinal edge is provided with fasteners 15 which cooperate with fasteners on the other panel 11 for retaining the panel 14 in place. A slide member 16 is provided for engaging and disengaging the fasteners.

The brassière of the present embodiment comprises the upper portions 17 of the side back 10 panels 12, 12, a back (not shown) and a front section stitched to the part 17 of one panel 12 and detachably secured by hooks and eyes 18 to the part 17 of the other panel 12. The sides and back of the brassière are non-elastic. Said front section comprises two side members 19 of non-elastic material, and a center front panel 20 of laterally elastic material. The panel 20 is narrower at its upper end than in the lower portion. The side members 19 are shorter than the panel 20 and are stitched at 21 to opposite sides of the lower portion of the panel 20. Breast pieces 22, 22, suitably shaped, are stitched at 23 to the upper edges of the members 19, 19, and to the upper side margins of the elastic panel 20. 25

A strip of elastic 24 is folded to V-form and stitched at 25 to the brassière members 19. A hook 26 on the strip 24 engages an eyelet 27 in the corset body. The strip 24, hook 26 and eyelet 27 are concealed by the brassière and they do not interfere with the elasticity of the panel 20. 30 Shoulder straps are indicated at 28.

When the invention is embodied in a combination corset and brassière, the front of the brassière is preferably detached from the corset, as shown. The invention may be embodied in corsets and brassières in which the center and side back members are not integral as herein shown.

The panel 20 of the brassière, in combination with its associated parts, exerts dia-phragm and bust control and enables the garment to be worn with comfort by a person whose waistline and bust measurements vary from the predetermined measurements from which the garment was designed. The brassière automatically adjusts itself to adjustments which may be made in the corset by means of the lacings or otherwise. The variation in the width of the panel 20 provides greater elasticity and easier stretchability in the lower portion than in the upper. This has been 50 carefully designed to meet practical requirements resulting in variations in waistline and bust measurements, without sacrifice of the supporting and controlling functions of the brassière.

Changes may be made in details of construction. 55

tion without departing from the scope of my invention and I do not intend to be limited to the exact form shown and described, except as set forth in the appended claims.

5 1. I claim:—

1. A foundation garment comprising a corset having front and side portions and a brassière portion separate from each other at the front along the lower edge thereof with the sides of 10 the brassière portion secured along the vertical front edges of the side portions, means in the front portion of the corset for positively varying and adjusting the width of the corset portion, and means in the brassière portion for automatically 15 adjusting the brassière to the body of the wearer and compensating for variations in the adjusted width of the front corset portion, said means consisting of a horizontally elastic panel extending from the upper edge to the lower 20 edge of the brassière portion and connected at its side margins to non-elastic portions of the brassière portion, the brassière portion overlying the adjustable corset portion and having greater elasticity in its lower than in its upper portion.

25 2. A garment including a brassière portion comprising a body having side members of non-elastic material, a horizontally elastic center front panel connected to said side members and extending from the top to the bottom of the 30 brassière portion, a V-shaped elastic strap attached at its ends to the opposite non-elastic side members adjacent said elastic panel and completely underlying the panel, and a hook on the strap.

35 3. A foundation garment comprising a corset portion and brassière portion, separate from each other at the front waistline, the front of the brassière portion consisting of two non-elastic side and breast covering members, an intermediate center front horizontally elastic panel stitched at each side margin to said members, the elastic panel being relatively narrow in the upper part between the breast covering members and approximately double said width in the lower 40 portion and extending from the upper to the lower edge of the brassière portion, a V-shaped elastic strap attached at its ends to the opposite non-elastic side members adjacent the elastic panel and completely underlying said panel, and 45 a hook on the strap for engaging a part of the corset front beneath the brassière portion.

50 4. A foundation garment comprising a corset portion and a brassière portion separate from each other at the front waistline, the brassière portion overlying the upper front of the corset portion, means at the front of the corset portion for varying the width of the corset portion, means in the brassière portion for automatically adjusting the brassière portion to the body of the 55

wearer to provide variations in the predetermined waist and bust measurements for which the garment was designed and compensating for variations in the width of the corset portion, said means consisting of a horizontally elastic panel 5 extending from the upper edge of the brassière portion to the lower edge, connected at its side margins to non-elastic portions of the brassière portion, a V-shaped elastic strap attached at its ends to the opposite non-elastic side members 10 adjacent the elastic panel and completely underlying said panel, and a hook on the strap for engaging a part of the corset front beneath the brassière portion.

5 5. A foundation garment comprising a corset portion and brassière portion separate from each other at the front waistline, the brassière portion overlying the upper front of the corset portion, means at the front of the corset portion for varying the width of the corset portion, means 15 in the brassière portion for automatically adjusting the brassière portion to the body of the wearer and compensating for variations in the width of the corset portion, said means consisting of a horizontally elastic panel extending from the upper edge of the brassière portion to the lower edge, connected at its side margins to non-elastic portions of the brassière portion, said 20 elastic panel being relatively narrow in the upper portion which lies between the breast covering parts of the brassière body and substantially wider in its lower portion, a V-shaped elastic strap attached at its ends to the opposite non-elastic side members adjacent the elastic panel and completely underlying said panel, and a hook on the strap for engaging a part of the corset front beneath the brassière portion.

6. A foundation garment comprising a corset portion and a brassière portion separate from each other at the front waistline, the brassière portion overlying the upper front of the corset portion, means at the front of the corset portion for varying the width of the corset portion, means in the brassière portion for automatically adjusting the brassière portion to the body of the 40 wearer and compensating for variations in the width of the corset portion, said means consisting of a horizontally elastic panel extending from the upper edge of the brassière portion to the lower edge, connected at its side margins to non-elastic portions of the brassière portion, said 45 panel having greater elasticity in its lower than in its upper portion, a V-shaped elastic strap attached at its ends to the opposite non-elastic side members adjacent the elastic panel and completely underlying said panel, and a hook on the strap for engaging a part of the corset front beneath the brassière portion.

CHARLES H. SCHOPBACH.
